United States Patent Office

Des. 218,413

Patented Aug. 18, 1970

218,413

FRONT PANEL UNIT FOR A VEHICLE

Jesse R. Birchard, Walled Lake, Mich., Albert D. Mortrude, Pompano Beach, Fla., and Ray C. Conner, Battle Creek, Mich., assignors, by mesne assignments, to The Cortez Corporation, Kent, Ohio, a corporation of Ohio

Original design application Sept. 20, 1968, Ser. No. 13,621. Divided and this application Feb. 26, 1969, Ser. No. 17,036

Term of patent 14 years

Int. Cl. D12—14

U.S. Cl. D14—6

FIG. 1

FIG. 2

FIG. 1 is a front elevational view of a front panel unit for a vehicle embodying our new design; and

FIG. 2 is a right side elevational view thereof.

The portion in broken lines is shown for illustrative purposes only.

This is a divisional application of application Ser. No. D. 13,621, filed Sept. 20, 1968.

We claim:

The ornamental design for a front panel unit for a vehicle, as shown and described.
